BOBBIN CASE FOR SEWING MACHINES

Stanley Ernest Frampton, Leicester, England, assignor to United Shoe Machinery Corporation, Borough of Flemington, N. J., a corporation of New Jersey

Application December 16, 1938, Serial No. 246,193
In Great Britain January 4, 1938

15 Claims. (Cl. 112—233)

The present invention relates to shoe sewing machines and is particularly, but by no means exclusively, concerned with outsole lockstitch sewing machines of the hook needle type, one example of which is described in U. S. Letters Patent of Gouldbourn et al., No. 2,056,670 of October 6, 1936.

In U. S. Letters Patent of Gouldbourn et al., No. 1,991,456 of February 19, 1935, there is described a cylindrical bobbin or locking thread case, for a rotary shuttle of a hook needle outsole sewing machine such as is described in Patent No. 2,056,670, having tension devices in the circular wall of the bobbin case which press the thread against an integral portion of the bobbin case wall, and in which time may cause said portion against which the thread is pressed to become worn in such a manner that the tension devices become ineffective. It then becomes necessary to replace the bobbin case by a new one. The bobbin case described in Patent No. 1,991,456 is supported by a pin, secured in the shuttle eccentric to the axis about which the latter rotates, and is held from completely rotating with the shuttle. It has been observed that if the pin in the shuttle, on which the bobbin case is supported, or the bobbin case becomes worn, other portions of the bobbin case are apt to come into contact with the rotating shuttle and to become so worn that the bobbin case is quickly rendered unfit for use.

The various objects of the present invention are to simplify the constructions and prolong the useful life of a bobbin or thread case in a machine such as is above referred to.

In an illustrative embodiment of the present invention there is provided a cylindrical bobbin or locking thread case having all the thread engaging parts including thread tensioning means and a wear member against which the tensioning means presses the thread, supported in a circular wall and readily renewable when worn. To avoid difficulty with projecting corners or angular edges on which particles of thread or other matter may accumulate, as hereinafter described, the surfaces of the wear member are curved and form continuations of the circular wall of the bobbin case. In the preferred form of the invention, the wear member is provided with a plurality of surfaces any of which may be located at a position to support the thread. In carrying out this feature of the invention, the wear member is retained in position by means embracing the circular wall of the thread case, and such an arrangement is of advantage

whether the thread tension device is renewable or not. In carrying out this feature of the invention, the wear member is grooved to provide a surface level with a peripheral groove in the circular wall of the bobbin case for receiving the means to retain the wear plate in place.

The renewable wear member of the illustrative embodiment has in its holes through one of which the shuttle thread passes from a thread reel in the case to the tension device, the latter being arranged in a groove extending around the outer circular face of the case. The features of the invention include the use of the same or a second renewable wear member in the curved wall of the bobbin case, forming part of the thread tension device against which the shuttle thread is pressed as it is passing from the bobbin case, said member or members being renewable by changing or reversing their individual positions. An additional renewable wear member is provided in one form of this feature, instead of the usual hole in the front face of the bobbin case, from which the shuttle thread passes after it leaves the tension device.

The bobbin case illustrated in the drawing is also provided with a renewable sleeve which receives and forms a bearing for the pin in the shuttle, on which pin the bobbin case is rotatably mounted.

The above and other objects, and the several features of the invention will become apparent to those skilled in the art from a consideration of the following description, given by way of example and with reference to the accompanying drawing.

In the drawing, Figure 1 is a view illustrating the peripheral circular face or wall of a cylindrical bobbin case embodying the present invention, as it would appear if laid out flat, with renewable bobbin thread engaging devices thereon; Figure 2 is a perspective view showing various parts of the bobbin case separated from each other; Figure 3 is a sectional view on an enlarged scale, taken along the line 3—3 of Figure 1; Figure 4 is a view of part of the circular peripheral face or wall of the bobbin case, as shown in Figure 1, with renewable wear devices of a different form; Figure 5 is a view of part of the peripheral face of the bobbin case as shown in Figure 4, but without the renewable devices; Figures 6 and 7 are views in front and side elevation, respectively, of the reversible and renewable wear device having in it holes through one of which the thread passes as it leaves the inside of the bobbin case; Figures 8 and 9 are similar views

of another reversible and renewable wear device cooperating with the thread tension; and Figure 10 is a sectional view of the bobbin case.

The illustrated bobbin or locking thread case 1 is of cylindrical or similar shape and is provided with shuttle thread contained in a reel or other thread supply package of usual construction rotatably mounted in the bobbin case, as indicated by dot-dash lines 5 of Figure 10. The bobbin case has formed in it a central boss 2 in which is a renewable sleeve 3, arranged to form a bearing for a pin (not shown) in the shuttle, on which pin the bobbin case is rotatably mounted and which may readily be replaced when wear occurs. The sleeve is formed with a shoulder within the thread case to locate its endwise position in the bobbin case, and with an enlarged portion extending beyond the boss 2 upon which is rotatably supported the bobbin reel or other thread package.

The bobbin case embodying the present invention has formed in its circular side wall faces 7, 9 (Fig. 3) in which is removably supported a single renewable wear member in the form of a curved perforated block 11. The curvature of the block 11 along its inner face, as shown in Figure 3, is such that it forms a continuation of the inner circular wall of the bobbin case. The outer face of the block is also curved and grooved to provide surfaces substantially level with the bottom face of a peripheral groove 13 extending around the bobbin case.

The block 11 is held in an opening 6 by yielding retainers in the form of a circular tension member 15, and a circular adjusting member 17, to be described more fully hereafter. The members 15 and 17 embrace the bobbin case within the groove 13 overlapping the block 11 to secure the block in place.

The block 11 has formed in it two perforations or holes 19 through one of which thread from the reel in the bobbin case passes. The block 11 has formed on its wear faces 21 at right angles to the bottom surface of groove 13 against one of which wear faces the shuttle thread is pressed by the tension member 15, the faces 21 being slightly undercut and rounded, as indicated at 23 (Fig. 2) at an end of each and sharp cornered at the other end, so that when the block is in place, in the bobbin case, there will be an accurate alinement between the two. The shuttle thread, after passing between the tension member 15 and one of the faces 21, passes over the rounded end of a face 21 towards one end of the thread case through an axial hole or eye 25 in a circular yielding guide member 27 which is positioned in a groove 29 extending around the circular wall of the thread case. When the sides of hole 25 in the member 27 wear unduly, the member may readily be renewed by springing the ends apart so that it may be removed from the groove 29. Also, when one of the holes 19 and/or one of the faces 21 becomes worn, the member 11 may be removed and be replaced on the bobbin case with the other hole and face reversed in position so as to be engaged by the thread. When both holes and faces become worn, the member may readily be renewed.

As the locking thread leaves the bobbin reel 5 in the embodiment of the invention illustrated in Figures 4 to 9 inclusive, the thread passes over a guide pin 30 secured in the bobbin case and extending across an opening 31 formed partly in the peripheral wall and partly in the front

wall of the case. The pin 30 may readily be replaced by a new one if it becomes worn by the passing of the shuttle thread over it in a direction axially of the thread case. This bobbin case has also formed in it two circular openings 33 and 35 which intersect each other, as shown in Figure 5, and each opening is counter-bored to form supporting faces 37 and 39.

In the opening 35, and supported by the face 39, is a disc-shaped renewable wear member or block 41 (Figures 6 and 7) which has formed in it two holes 43 through one of which the shuttle thread passes, as shown in Fig. 4. The member 41 has a comparatively thin central portion in which are formed the holes 43, and at each end of the central portion is a flange arranged to be supported on the face 39. The inner face 45 of the central portion of the member 41 is substantially level with the inner peripheral face of the bobbin case, and the outer face 47 of the central portion is substantially level with the bottom face of a groove similar to the groove 13 extending around the bobbin case.

In the opening 33, and supported by the face 37 is another disc-shaped renewable wear member or block 49. The member 49 has a central portion, the inner face 51 of which is substantially level with the inner peripheral face of the bobbin case and the outer face 53 of which is substantially level with the bottom face of the groove 13 in the bobbin case. The member 49 has formed on it faces 55 against one of which the shuttle thread is pressed by a tension member, similar to the member 15 above referred to, after it leaves the hole 43 in the member 41, as shown in Figure 4. The faces 55 are slightly undercut and rounded, as indicated at 57, to provide a rounded corner around which the thread passes. When one of the holes 43 or faces 55 become worn, the position of either of the members 41 and 49 on the bobbin case may readily be reversed to bring any other hole or face of member 41 into operative position and, when both holes and faces of the member are worn, the worn members may readily and comparatively cheaply be replaced by new ones.

The members 41 and 49 are prevented from rotating in the circular openings 33 and 35 by their engagement with each other, the corners 59 of member 41 being bevelled off somewhat to provide faces for engagement with the member 49, and the two members are held in the openings by retainer members similar to the aforesaid tension member 15 and tension adjusting member 17, above referred to, which extend partly around the bobbin case 1 in the groove 13.

The member 15 in both modifications has on it a projection 61 which enters a recess in one wall of the groove 13 and prevents the member 15 from moving around the bobbin case. The tension member 15 also has another projection 63 at one end of it which engages in one of a series of recesses 65 formed in the adjusting member 17. The other end of the member 15 presses the shuttle thread against one face on the wear member. The member 17 has a tapered portion 67, one face of which engages a curved part 69 of the member 15. If the member 17 is adjusted around the bobbin case the tapered portion 67 causes the member 15 to press more or less firmly against the thread and thus varies the tension on the thread. The adjusting member 17 is held in adjusted posi-

tion by the engagement of one of the recesses 65 with the projection 63.

The form of the renewable part 11 shown in Figures 1 and 2 is somewhat cheaper to produce than the two parts 41 and 49 shown in Figures 4 to 9 inclusive, and the hole in the guide member 27 provides a considerably greater wearing surface than the pin 30, the hole 25 being so arranged in the member 27 as to provide as much material as possible between the hole and the outer surface of the member, as shown in Figure 1, to be worn away before the member requires renewing.

In the illustrative embodiments there are thus provided a durable bobbin case of comparatively simple and inexpensive form with readily renewable parts which are engaged by the shuttle or locking thread and are liable to become worn by the pressing of the thread against them as it leaves the case.

Having now described the nature of the present invention, what is claimed is:

1. A shuttle thread supply device for a lock-stitch shoe sewing machine having, in combination with a cylindrical bobbin thread case, readily renewable thread engaging parts mounted in a circular wall of the thread case comprising a tension device, and a wear member having a surface level with a surface of the thread case against which the tension device presses the thread.

2. A shuttle thread supply device for a lock-stitch shoe sewing machine having, in combination with a cylindrical bobbin thread case, readily renewable thread engaging parts mounted in a circular wall of the thread case comprising a tension device, and a wear member against which the tension device presses the thread comprising a curved block provided with a plurality of surfaces, any of which may be located in a position to support the thread along that portion pressed by the tension device.

3. A shuttle thread supply device for a lock-stitch shoe sewing machine having, in combination with a cylindrical locking thread case, readily renewable thread engaging parts in the thread case comprising a wear member along which the thread passes, and means embracing a circular wall of the thread case for holding the wear member in place.

4. A shuttle thread supply device for a lock-stitch shoe sewing machine having, in combination with a cylindrical locking thread case, readily renewable thread engaging parts in the thread case comprising a wear member along which the thread passes, a yielding tension device embracing the thread case and acting to press the thread against the wear member and to hold the wear member in place.

5. A shuttle thread supply device for a lock-stitch shoe sewing machine having, in combination with a cylindrical locking thread case having a peripheral groove about its circular wall, readily renewable thread engaging parts in the circular wall of the thread case comprising a block provided with surfaces level with the bottom face of the groove in the circular wall, and means within the groove of the thread case overlapping the block to hold it in place.

6. A shuttle thread supply device for a lock-stitch shoe sewing machine having, in combination, a cylindrical locking thread case having a peripheral groove about its circular wall, readily renewable thread engaging parts in the circular wall of the thread case comprising a block pro-

vided with a wear face in alignment with one lateral edge of the groove in the thread case, and means mounted within the groove for pressing the thread against said wear face and for holding the block in place.

7. A shuttle thread supply device for a lock-stitch shoe sewing machine having, in combination, a cylindrical locking thread case having a peripheral groove about its circular wall, readily renewable thread engaging parts in the circular wall of the thread case comprising a block provided with a wear face in alignment with one lateral edge of the groove in the thread case, means mounted within the groove in the thread case for pressing the thread against the wear face of the block and for holding the block in place, and renewable means to direct thread passing from the wear face of the block at right angles to the wear face axially towards one end of the thread case.

8. A shuttle thread supply device for a lock-stitch shoe sewing machine having, in combination, a cylindrical locking thread case having a peripheral groove about its circular wall, readily renewable thread engaging parts in the circular wall of the thread case comprising a block provided with a wear face in alignment with one lateral edge of the groove in the thread case, means mounted within the groove in the thread case for pressing the thread against the wear face of the block, and for holding the block in place, and a yielding renewable member extending around the circular wall of the thread case and having a thread eye for guiding the thread passing from said wear face axially towards one end of the thread case.

9. A shuttle thread supply device for a lock-stitch shoe sewing machine having, in combination, a cylindrical locking thread case having a peripheral groove about its circular wall, readily renewable thread engaging parts in the circular wall of the thread case comprising a block provided with a wear face in alignment with one lateral edge of the groove in the thread case, means mounted within the groove in the thread case for pressing the thread against the wear face of the block, and for holding the block in place, a renewable guide member for directing the thread passing from said wear face axially towards one end of the thread case, and a renewable wear member having rounded corners about which the thread passes from the block to the guide member.

10. A shuttle thread supply device for a lock-stitch shoe sewing machine having, in combination with a cylindrical locking thread case, readily renewable thread engaging parts in the thread case comprising a wear member having angularly disposed surfaces along one of which the thread passes, and a tension member for pressing the thread against the wear member and for engaging the other surface of the wear member to hold it in place.

11. A shuttle thread supply device for a lock-stitch shoe sewing machine having, in combination with a cylindrical locking thread case having a peripheral groove, readily renewable thread engaging parts in a circular wall of the thread case comprising a grooved wear member having angularly disposed surfaces along its grooved portion, and a circular tension member embracing the groove in the thread case to press the thread against one of the surfaces of the wear member and to hold the wear member in place by engaging another of said surfaces.

12. A shuttle thread supply device for a lock-stitch shoe sewing machine having, in combination with a cylindrical locking thread case, readily renewable thread engaging parts in the thread case, comprising means for directing the thread circumferentially along a circular side wall of the thread case, and a replaceable pin extending across an opening in the thread case for guiding the thread axially of the thread case along said side wall.
13. A shuttle thread supply device for a lock-stitch shoe sewing machine having, in combination with a cylindrical bobbin thread case, readily renewable thread engaging parts mounted in a circular wall of the thread case comprising a tension device and a renewable block provided with holes arranged to be located readily in one of a number of positions to permit the thread from within the thread case to pass through any one of the holes to the tension device depending upon the position of the block.
14. A shuttle thread supply device for a lock-stitch shoe sewing machine having, in combination with a cylindrical bobbin thread case, readily renewable thread engaging parts mounted in a circular wall of the thread case comprising a tension device and a renewable block having holes for guiding the thread through the wall of the thread case, said block being so shaped that it will fit in the thread case in more than one position with one of the holes located to guide the thread in any of said positions.
15. A bobbin thread supply device for a lock-stitch shoe sewing machine having, in combination, a cylindrical locking thread case provided with a central bearing on which the thread case is rotatably supported, and a renewable sleeve within the bearing formed with an enlarged shoulder portion extending beyond the bearing to rotatably support a thread supply reel.

STANLEY ERNEST FRAMPTON.
